SKATE BOARD SCOOTER

Phillipp Gonzalez, 2730 W. 15th St.,
Los Angeles, Calif. 90006

Filed Aug. 22, 1969, Ser. No. 18,813

Term of patent 14 years

Int. Cl. D12—11

U.S. Cl. D34—15

Fig. 2

Fig. 3

Fig. 4

Fig. 5

Fig. 6

FIG. 1 is a perspective view of a skate board scooter showing my new design;

FIG. 2 is a top plane view thereof;

FIG. 3 is a left side elevational view of the new design article, the opposite side being a mirror image thereof;

FIG. 4 is a bottom plan view of the article shown in FIG. 1;

FIG. 5 is a front elevational view of the design article; and

FIG. 6 is a rear elevational view thereof.

I claim:

The ornamental design for a skate board scooter, substantially as shown and described.
